UNITED STATES PATENT OFFICE.

FRANCES McCLURG, OF NEW YORK, N. Y.

DESIGN FOR A TOY.

48,790.

Specification for Design. Patented Mar. 28, 1916.

Application filed February 1, 1916. Serial No. 75,611. Term of patent 3½ years.

To all whom it may concern:

Be it known that I, FRANCES McCLURG, a citizen of the United States, and a resident of the city, county, and State of New York, have invented a new, original, and ornamental Design for Toys, of which the following is a specification, reference being had to the accompanying drawings, forming part thereof.

In the drawings, Figure 1 is a side elevation; Fig. 2 is a front elevation; and Fig. 3 is a rear elevation of a toy embodying my new design.

I claim:

The ornamental design for a toy as shown.

FRANCES McCLURG.
